MONROE GUETT, OF HARTFORD, CONNECTICUT, ASSIGNOR TO THE HART & HEGEMAN MANUFACTURING COMPANY, OF HARTFORD, CONNECTICUT, A CORPORATION OF CONNECTICUT.

LOW-VOLTAGE ELECTRIC SWITCH.

1,254,223.

Specification of Letters Patent. Patented Jan. 22, 1918.

Application filed June 22, 1917. Serial No. 176,296.

To all whom it may concern:

Be it known that I, MONROE GUETT, a citizen of the United States, residing at Hartford, in the county of Hartford and State of Connecticut, have invented a new and useful Improvement in Low-Voltage Electric Switches, of which the following is a specification.

This invention relates to an electric switch of the type which is particularly designed for opening and closing battery circuits, such, for instance, as those used on automobiles and other vehicles in the lighting, ignition and starting systems.

The object of the invention is to provide a very cheap, small and durable switch that can be readily installed and easily manipulated for efficiently opening and closing a low tension circuit.

As manufactured and placed on the market switches of this character are quite small and all of the views of the accompanying drawing are on an enlarged scale. Figure 1 shows a face view of the switch. Fig. 2 shows a side view. Fig. 3 shows a longitudinal section on plane 3—3 on Fig. 1. Fig. 4 shows a transverse section on line 4—4 on Fig. 3. Fig. 5 is a view looking into the receptacle, the face plate, operating button and blade being removed. Fig. 6 is a view looking at the bottom of the receptacle with the terminal plates in place. Fig. 7 is a view looking at the bottom of the receptacle with the terminal plates and insulation removed. Fig. 8 is a view of one of the insulating disks employed on the inside and outside of the bottom of the receptacle. Fig. 9 is a view of one of the insulating washers which are placed in the openings in the bottom of the receptacle and between the insulating disks.

The receptacle 1 of the switch shown is a cup of thin sheet metal with ears 2 extending outwardly from its open end. In the bottom of the receptacle are two elongated perforations 3. Washers 4 of insulating material are located in the circular portions of the perforations in the bottom of the receptacle, and inside and outside of the bottom are placed disks 5 of insulating material. Each of these disks has two circular openings 6 and four angular openings 7.

The feet 8 of the spring fingers 9 are seated on the insulating disk on the inside of

the bottom of the receptacle. The fingers 55 near their free ends have bosses 10 struck out so as to face each other. The feet have central openings that align with the circular openings in the disks and notches 11 in their edges that align with the angular openings in the disks.

The terminal plates 12 are seated on the insulating disk on the outside of the bottom of the receptacle. These plates have circular openings that align with the circular 65 openings in the disks and they have lugs 13 that extend through the angular openings in the disks and into the notches in the edges of the finger feet. These parts thus assembled are secured in place and the 70 terminal plates and fingers are electrically connected by eyelets 14 that are passed through the circular openings in the terminal plates, disks, washers and feet and are headed over at both ends. The eyelets 75 are interiorly threaded for the reception of the binding screws that are employed for the attachment of the ends of the circuit wires. In this simple and cheap manner the 80 spring fingers are connected in the circuit and are insulated from the receptacle and from each other.

The face plate 15 is stamped to the desired outline from thin sheet metal and is fastened over the open end of the receptacle by screws 16 which turn through the plate into the ears that project from the open end of the receptacle. The switch blade 17 is cut from a thin sheet of insulating material of a width substantially the 85 same as the interior diameter of the receptacle. The stem 18 of the blade extends through a slot in the face plate and on the outside is secured to the operating button 19. In the switch blade is a perforation 20 95 containing no metal and a perforation that is occupied by an eyelet 21 which is headed over at both ends to hold it in place. All of the parts of this simple switch are easy to manufacture and assemble and the whole 100 structure is very cheap and compact.

When the button is pushed in the spring fingers are separated by the thin insulating blade, and under these conditions the circuit is opened. While the blade is in this 105 position the bosses in the ends of the spring fingers enter the perforation 20 and retain the blade against accidental movement. If

the blade is pulled out the spring fingers engage the eyelet 21 and thus become electrically connected so that the circuit will be closed. The entry of the bosses on the 5 fingers into the eyelet opening retains the blade in this position.

The invention claimed is;

1. An electric switch having a cup-shaped receptacle, a face plate closing the upper 10 end of the receptacle, a piece of thin sheet insulating material extending diametrically across and movable inward and outward within the receptacle, said insulating piece having two perforations through it flatwise 15 within the receptacle and having a stem that extends through the face plate, a metallic eyelet fixed in one of said perforations and extending from wide face to wide face of said insulating piece, and a pair of conducting spring fingers having their inner 20 ends secured to the bottom of the receptacle and their outer ends pressing against the wide faces of said insulating piece, said fingers being provided with bosses struck 25 out toward each other from near their outer ends which bosses are adapted to fit into the opening through the eyelet when the insulating piece is drawn outward and enter the

unoccupied perforation when the insulating piece is moved inward.

2. An electric switch having a cup-shaped metallic receptacle, a slotted metallic face plate closing the upper end of the receptacle, a piece of thin sheet insulating material extending diametrically from side to side and 35 movable inward and outward within the receptacle, said insulating piece having two perforations through it flatwise within the receptacle and having an integral stem that extends through the slot in the face plate, a 40 metallic eyelet fixed in one of said perforations and extending from wide face to wide face of said insulating piece, and a pair of conducting spring fingers having their inner ends secured to but insulated from the bottom of the receptacle and their outer ends 45 pressing against the wide face of said insulating piece, said fingers being provided with bosses struck out toward each other from near their outer ends which bosses are 50 adapted to fit into the opening through the eyelet when the insulating piece is drawn outward and enter the unoccupied perforation when the insulating piece is moved inward.

MONROE GUETT.
